UNITED STATES PATENT OFFICE.

HENRY S. HALLWOOD, OF COLUMBUS, OHIO, ASSIGNOR TO THE CITY NATIONAL BANK, OF COLUMBUS, OHIO.

CASH-REGISTER.

1,385,540.

Specification of Letters Patent. Patented July 26, 1921.

Application filed April 11, 1914. Serial No. 831,108.

To all whom it may concern:

Be it known that I, HENRY S. HALLWOOD, a citizen of the United States, residing at Columbus, in the county of Franklin and 5 State of Ohio, have invented a certain new and useful Improvement in Cash-Registers, of which the following is a full, clear, and exact description, reference being had to the accompanying drawings.

10 The broad principle of this invention is shown and claimed in my Letters Patent 1,078,920 filed Nov. 4, 1899; 1,085,680 filed Sept. 1, 1900; and 845,634 filed Oct. 22, 1906.

15 The present improvement relates to specific details of a simplified construction adapted to perform similar functions and produce the same results.

20 The particular object of this invention is to simplify the interlocks shown and described in the Letters Patent to Edward J. Von Pein #938,527, November 2, 1909, in which a very large number of toggle jointed devices are shown to lock the department registers, the grand total register, the main 25 operating shaft, and all actuating mechanism moved thereby against operation until four separate locks have been released by a predetermined sequence of key setting operations in which, the middle series must 30 always be operated last, always after the valve keys, and always after the pinch lever carried by the selective register lever.

35 In registers of this type the key board is arranged with the value keys on the right, and the selective register keys one for each register on the left, labeled with letters for clerks or words for departments, but the identification keys, which may be labeled with letters or words, are between the selective 40 register keys and the value keys, and this center series no matter how labeled, are normally ineffective and functionless until the pinch lever has been pinched and a value key depressed before an identification key 45 or register is rendered effective.

50 This invention provides for placing all the register actuating mechanism under control of the two setter dogs herein shown whereby the actuating mechanism will not be released or the electric circuit closed until each setter dog is set in upset position.

55 For this purpose I attach to one locking dog a bridle having a plurality of tails one

for each denomination, each tail adapted to oscillate said dog out of the recess 15 whenever any dog stud 10 is oscillated by the depression of any tail by any value key. A similar but independent dog having only one tail, is used for the identification series 60 which may be captioned as desired, initials, departments or both. The various selective registers are normally movable and one is always in position for the next registration, but all of them are inoperative for registration purposes until both of the dogs have had a tail pushed down by both a value key, and an identification key. It is immaterial, however, whether the labels bear letters or words, but under all conditions, a selective 70 key must be used for changing a register and its indicator with corresponding type into indicating, adding and printing position, an identification key must also be used for indicating, printing and releasing a dog, 75 and a value key must also be used before a complete registration and record is possible, and thus each clerk is compelled to operate both a value and an identification key before a new transaction can be indicated, registered and recorded. 80

The pinchless lever herein shown when between stations prevents the depression of an identification key and the release of the machine, and until a register is in proper 85 position to receive the next registration, but under no circumstances can foolish indications, registrations, or records be made such as are now possible on all registers of the 500 class. 90

It is obvious that these separate and independent dogs compel the depression without sequence of both a value key and an identifying key (labeled with a word or initial) before any indication, registration or record 95 can be made and at the same time discards with the pinching of the pinch lever.

This invention differentiates from the prior art by placing the distinct elements of selection, indication, registration, identification, actuation, and record under the control of two simple locks, which renders the machine accurate and prevents foolish indications and records, by compelling the clerk to operate both a value key and an identification key before any part of the machine 100 can be operated. 105

In the accompanying drawings Figure 1

is a view of the left side of a part of a cash register containing my invention.

Fig. 2 is a transverse section on line 1—1 of Fig. 3.

5 Fig. 3 is a plan view of the parts shown in Figs. 1 and 2.

Fig. 4 is a detail in horizontal section on line 2—2 of Fig. 2.

10 Fig. 5 is a front elevation of Fig. 3 and shows the indicators B, registering wheels D.

Fig. 6 is a view similar to Fig. 1.

Fig. 7 is a plan view of Fig. 6.

15 Fig. 8 is a sectional view of the recorder shown in Fig. 13 of the Hallwood Patent 845634.

This invention differentiates from the device described in claim 62 of this applicant's Patent 1078920 in which there are three species of keys for numbers, letters and 20 words, two of which unlock the main operating member, thereby creating an incomplete indication and record.

But to compel the use of all three species and thereby a complete indication, registration 25 and record, in numbers, letters and words the three cycle interlocks shown described and claimed in Patents 1085680 and 845634, are so correlated and co-active as to compel the operation of a key in three 30 species.

In this invention, there are three species also but the locks are independent and purposely designed to be responsive to many 35 claims in 1085680 and to 73 and 77 of 845634, so as to be protected thereby.

In the above described drawings 1 represents a bank of value keys—one for each 40 denomination. 2 represents a bank of identifying keys. 3 represents a series of identifying characters by which are determined 45 different positions of adjustment of the register selecting lever 3^a. The several banks of keys and the series of identification characters before mentioned are arranged concentric to a shaft 4 which is supported at 50 each end by side plates in the usual manner as shown in Von Pein 938,527. Detent frames 5 are mounted on the shaft 4 and are operated by the keys in the usual manner. 6 represents the main driving shaft to 55 which power is applied either by a hand crank (not shown) through the gear 7 mounted thereon, as shown in the patents referred to, or by an electric motor 7^a through the worm wheel 8 and bevel gears 9.

60 Mounted on the main drive shaft 6 are disks 16 one at the rear of the identifying key bank and the other at the rear of the group of value key-banks. A notch 15 is formed in each of the disks 16 adapted to receive the free ends of dogs 13 which are fulcrumed on the shaft 12. The dog 13 of the identifying bank extends forward of the shaft 12 and is formed with a beveled 65 end which is adapted to be engaged by a

stud 10 projecting from the side of the detent frame 5 of said identifying key bank 2.

The dog 13 of the value key banks is formed as a bridle which extends across the said value key banks. A lever 11 having a 70 shoulder 11^a is fulcrumed on the shaft 12 in the rear of each value bank 1. The forward end of said lever having a beveled face similar to dog 13, adapted to be engaged by the stud 10 on the detent while the 75 shoulder engages the forward edge of the bridle bar and oscillates it when the forward end of the dog is depressed.

The two levers 17 are fulcrumed on a cross bar 18 of the register frame, and one end 80 of each is adapted to bear on one of the contact bars 19 which are included in the electric circuit 7^b controlling the motor 7^a, the opposite end of each of said levers 17 is adapted to be engaged by an extension 20 85 on the dogs 13 in such a manner that when a dog 13 is lifted out of the notch 15, the free end of a lever 17 is depressed.

A group of registers 21 for either clerks or departments is mounted on a reel which 90 is adapted to be turned by the lever 3^a to bring the desired register to operative position as shown in said Von Pein patent.

This lever is provided with a spring bolt 95 24 which, when the lever is in proper position, is engaged by one of a series of notches 25 formed on the register index frame. These notches are so formed as to give only slight resistance to the movement of the lever from one notch to another. To prevent the 100 identifying keys from being operated while the spring bolt 24 is out of a notch, a plate 26, having notches 27, is adapted to embrace the lever 3^a when set in a proper position. This plate lies on the periphery of the selective 105 index adding frame and is given a lateral movement, by the pins 28 and the slots 29.

This lateral movement of the plate 26 is caused by the depression of any one of the 110 identifying keys 2, the cross pins of which extend laterally and bear against the inclined edge 30 of a segment plate 31 having slots 32 by which it is supported and guided by the pin 33 and the rock shaft 34.

115 The rock shaft 34 is supported by the selective register index and identifying key frames and carries a rock arm 35, the free end of which is connected to the plate 31 by a pin, and is rocked when the plate 31 is raised by the depression of any key 2. Another rock arm 35 is fixed on the shaft 34 adjacent to the register index frame, and its free end is connected to a bar 37 which projects upwardly and parallel to the plate 120 26. Said bar 37 connects two levers 38 which are fulcrumed on pins 39 projecting from the under side of a cover plate 40. On the free ends of the levers 38, a pin 41 projects into a slotted opening 42 in the plate 26. 125 130

The construction being such that when the levers 38 are moved, the plate 26 will be forced toward the lever 3^a and hold it in one of the notches 27, and it is equally obvious that if the plunger 24 is not in one of the notches 25 that all of the keys 2 will be locked against depression.

When the key lever 3^a is set in the desired position (for a repeat sale, it need not be touched) one or more value keys and an identifying key are depressed, whereby the dogs 13 are raised out of the notches 15 of the disks 16, and the extensions 20 are caused to oscillate the levers 17 to depress the bars 19 against contact points, and thus complete the circuit and start the motor. The construction is such that the circuit will not be completed until both bars 17 are in contact, and thus the driving shaft 12 is prevented from rotation if either one of the disks is locked by its dog, thereby making it compulsory to depress both a value and an identifying key before the machine can be operated, or a department key made effective for registration purposes.

It will thus be apparent that in this improvement I have not departed from the spirit of my former inventions herein cited, but that I have greatly improved upon the two, three and more cycle locks shown in the prior art by means of which the construction is greatly simplified and the result desired is secured by the least possible number of elements, the primary object being to compel the use of both a value key and an identifying key, before a new transaction can be indicated, registered and recorded.

While in the drawing the series of keys 2 have been shown as transaction identification keys and the lever 3^a and identification tablets 3 are shown as clerk identification means, it is obvious that these identification elements may be transposed and the series 2 of keys may be employed for identifying clerks and the lever and its coacting parts may be employed for identifying transactions. This is merely a matter of changing the designation or tablets and necessitates no change in the mechanism or operation.

In the appended claims the value keys, the transaction keys and the clerks keys or lever have been collectively termed "operation determining elements" inasmuch as they control and determine the performance of the operating mechanism. They have been separately classified as "amount determining elements" and "identification determining elements," the latter term being applicable whether the keys or the lever are employed for designating either clerks or transactions.

Having thus described my invention, what I desire to secure Letters Patent for, is expressed in the following claims:

1. A registering and accounting machine of the type embodying an intermittently actuated operating mechanism including a master element common to a plurality of manipulative value determining elements 70 and identity determining elements arranged in separate series and each having a part in governing the performance of said operating mechanism, characterized by a locking detent normally engaged in locking position 75 to prevent the operation of said master element and means controlling the detent to disengage it from said master element by the manipulation of an amount determining element independent of the operation of an 80 identity determining element.

2. In a machine of the character described, the combination with an operating mechanism, electrically operated actuating means therefor, a normally open electric circuit 85 controlling same and manipulative amount determining and identity determining elements controlling the performance of the operating mechanism of an electrical contact member in said circuit closed and controlled 90 by the operation of an amount determining element independent of the operation of an identity determining element.

3. A registering and accounting machine of the type embodying an intermittently actuated operating mechanism including a master element common to a plurality of manipulative value determining elements 95 and identity determining elements arranged in separate series and governing the performance of said operating mechanism, characterized by a plurality of independently operated control devices simultaneously preventing the operation of said master element and means for controlling one of said control devices wholly by the manipulation of a value determining element independent of the manipulation of an identity determining element.

4. A registering and accounting machine 110 of the type embodying an intermittently actuated operating mechanism including a master element common to a plurality of manipulative value determining elements and identity determining elements arranged 115 in separate series and governing the performance of said operating mechanism, characterized by separate independently operated locking detents for said master element simultaneously engaged therewith and independently rendering the master element inoperative, and independent operative connections between one of the locking detents and the identity determining elements and between the other detent and the value determining elements whereby one of said detents is controlled wholly by the manipulation of a value determining element and the other is controlled wholly by the manipulation of an identity determining element. 120 125 130

5. A registering and accounting machine of the type embodying an intermittently actuated operating mechanism including a master element common to a plurality of manipulative value determining elements and identity determining elements arranged in separate series and governing the performance of said operating mechanism, characterized by separate independently operated control devices for the master element, simultaneously and independently rendering the master element inoperative, and means controlled solely by the value determining elements for counteracting the effect of one of said control devices independent of the operation of an identity determining element, and means controlled solely by the operation of an identity determining element for counteracting the effect of the other control device independent of the operation of a value determining element.
6. In a machine of the character described, the combination with an operating mechanism, electrically operated actuating means therefor, an electric circuit controlling same and manipulative amount determining and identity determining elements controlling the performance of the operating mechanism, of separate independently operated contact members in said electric control circuit and means controlled by the operation of an amount determining element for operating one of said contact members independent of the operation of an identity determining element, and means controlled by the operation of an identity determining element for operating the other contact independent of the operation of an amount determining element.
7. In a machine of the character described, the combination with an operating mechanism, normally, inoperative electrically driven actuating mechanism therefor, an electric control circuit and manipulative amount determining and identity determining elements controlling the performance of the operating mechanism, of a mechanically operated locking detent and an electrical contact member in said circuit simultaneously rendering the operating mechanism normally ineffective and means controlled by the operation of an amount determining element for disengaging said detent and closing said contact independent of the operation of an identity determining element.
8. In a machine of the character described, the combination with an operating mechanism, normally inoperative electrically driven actuating mechanism therefor, an electric control circuit, and manipulative amount determining and identity determining elements controlling the performance of the operating mechanism, of separate mechanically operated detents and separate

electrical contact members normally rendering the operating mechanism ineffective, and means for controlling one of said detents and one of said contacts by the operation of an amount determining element independent of the operation of an identity determining element and means for controlling the other detent and the other contact member by the operation of an identity determining element independent of the operation of an amount determining element.

9. In a machine of the character described, the combination with an operating mechanism, normally inoperative electrically driven actuating mechanism therefor, an electric control circuit, and manipulative amount determining and identity determining elements controlling the performance of the operating mechanism, of a mechanically operated locking detent and an electrical contact member in said circuit simultaneously rendering the operating mechanism normally ineffective and means for controlling the operation of the electrical contact member by the operation of an amount determining element independent of the operation of an identity determining element, and means for controlling the mechanically operated detent by the operation of an identity determining element independent of the operation of an amount determining element.

10. In a machine of the character described, the combination with an operating mechanism, normally inoperative electrically driven actuating mechanism therefor, an electric control circuit, and manipulative amount determining and identity determining elements controlling the performance of the operating mechanism, of a mechanically operated locking detent and an electrical contact member in said circuit simultaneously rendering the operating mechanism normally ineffective and means for controlling the operation of the mechanically operated detent by the operation of an amount determining element independent of the operation of an identity determining element and means for controlling the operation of the electrical contact member by the operation of an identity determining element independent of the operation of an amount determining element.

11. A registering and accounting machine of the type embodying an intermittently actuated operating mechanism common to a plurality of manipulative value determining elements, arranged in a plurality of separate series, and a plurality of identity determining elements arranged in additional series each having a part in governing the performance of said operating mechanism, characterized by a mechanically operated detent common to a plurality of series of value determining elements, and normally locking the operating

- mechanism against operation, and interconnecting means between such detent and the several series of value determining elements whereby the operation of a value determining element in any one of said several series of value determining elements will effect the release of the operating mechanism from said detent independent of the operation of any other determining element in the same series or any other series of determining elements pertaining to either values or identity.
12. In a machine of the character described, the combination with an operating mechanism including a rotary shaft, and manipulative amount determining and identity determining elements arranged in a plurality of series and controlling the performance of the operating mechanism, of an oscillatory member common to all the manipulative determining elements of each series and adapted to be oscillated by the operation of any one of the manipulative determining elements of such series, a mechanically operated detent common to a plurality of such series of manipulative elements normally locking said rotary shaft against operation, a movable bridle upon which the detent is carried, and a plurality of extensions on said bridle extending into the paths of the oscillatory members pertaining to the several series of determining elements to which the detent is common whereby the oscillation of any one of the oscillatory members under the influence of a manipulative determining element pertaining thereto will operate said bridle to disengage the detent from the rotary shaft independent of the operation of any other determining element in the same series or in any other series of such elements.
13. A registering and accounting machine of the type wherein the performance of an operating mechanism common to a plurality of manipulative amount determining elements and identity determining elements arranged in a plurality of separate series is governed by said determining elements, characterized by two mechanically operated locking detents normally simultaneously positioned to prevent the operation of the operating mechanism, one of said detents being common to a plurality of series of such determining elements and means for controlling said detent wholly by the operation of any element of any one of the plurality of related series, and means for controlling the other detent wholly by the operation of a determining element of a different series, the operation of the controlling means pertaining to each detent and disengagement of each detent being entirely independent of the operation of the controlling means and disengagement of the other detent.
14. A registering and accounting machine embodying an operating mechanism and rotary actuating means therefor and a plurality of manipulative value determining elements and identity determining elements arranged in a plurality of series and jointly controlling the performance of the operating mechanism, characterized by, a mechanically operated locking detent normally locking the actuating mechanism against operation, and common to a plurality of series of determining elements and means to control said detent solely by the manipulation of any element of any one of said plurality of series, independent of any manipulation of an element in any additional series.
15. A registering and accounting machine embodying operating mechanism including a rotary actuator, the performance of which is jointly controlled by manipulative value determining elements and identity determining elements arranged in a plurality of series, characterized by a control device for the rotary actuator normally rendering the operating mechanism inoperative and common to a plurality of series of determining elements, and means for releasing the actuator by the manipulation of a determining element in any series of such elements to which said control device is common independent of the operation of any other determining element in the same or any other series, of such elements.
16. A registering and accounting machine embodying operating mechanism including a rotary actuator, the performance of which is controlled by manipulative value determining elements and identity determining elements arranged in a plurality of series, characterized by separate independently operated control devices for the rotary actuator simultaneously rendering the actuator normally ineffective, one of said control devices being common to a plurality of series of determining elements and means for actuating said control device wholly by the manipulation of any determining element of any series to which the control device is common independent of the operation of any other determining element in the same or any different series, and means for controlling the second control member wholly by the operation of a determining element in a different series of such determining elements independent of the operation of the first mentioned control device.
17. In a machine of the character described, the combination with an electrically driven operating mechanism, an electrical control circuit therefor, and manipulative operation determining elements arranged in a plurality of series and controlling the performance of the operating mechanism, of an electrical contact member in said circuit common to a plurality of series of manipulative determining elements normally rendering

- the operating mechanism ineffective and means for controlling said electrical contact member by the operation of a manipulative determining element in any of the plurality 5 of series of such elements to which said contact member is common independent of the operation of any other determining element in the same series or in any other series of such elements.
- 10 18. In a machine of the character described, the combination with an electrically driven operating mechanism, an electrical control circuit therefor, and manipulative operation determining elements arranged in a plurality of series and controlling the performance of the operating mechanism, of an electrical contact member in said circuit common to a plurality of series of manipulative determining elements normally rendering 15 the operating mechanism ineffective, means for controlling said contact member by the operation of a manipulative determining element in any series of the plurality to which said contact member is common 20 independent of the operation of any other element in the same series or in any other series, and a second electrical contact member normally rendering the mechanism ineffective and means for controlling said second contact member by the operation of a manipulative element in a separate series of such elements independent of the operation 25 of the first mentioned contact member.
19. In a machine of the character described, the combination with an electrically driven operating mechanism, an electrical control circuit therefor, and manipulative operation determining elements arranged in a plurality of series and controlling the performance 30 of the operating mechanism, of an electrical contact member in said circuit common to a plurality of series of manipulative determining elements normally rendering the operating mechanism ineffective, means for controlling said contact member by the operation of a manipulative determining element in any series of the plurality to which said contact member is common independent of the operation of any other 35 element in the same series or in any other series, and a mechanically operated detent also normally rendering the operating mechanism ineffective controlled by the operation of a manipulative determining element in a separate series of such elements independent of the operation of a determining element in any other series.
20. In a machine of the character described, the combination with an electrically driven operating mechanism, an electrical control circuit therefor, and manipulative operation determining elements arranged in a plurality of series and controlling the performance 40 of the operating mechanism, of a mechanically operated detent common to a plurality of series of manipulative determining elements normally rendering the operating mechanism ineffective, means for controlling said contact member by the operation of a manipulative determining element in any series of the plurality to which said contact member is common independent of the operation of any other element in the same series or in any other series, and a second mechanically operated detent by the operation of a manipulative determining element in any series of the plurality to which said detent is common independent of the operation of any other element in the same series or in any other series, and an electrical contact member in said circuit also normally rendering the operating mechanism ineffective controlled by the operation of a manipulative determining element in a separate series of such elements independent of the operation 45 of a determining element in any other series of elements.
21. In a machine of the character described, the combination with an electrically driven operating mechanism, an electrical control circuit therefor, and manipulative operation determining elements arranged in a plurality of series and controlling the performance of the operating mechanism, of a mechanically operated locking detent for 50 the operating mechanism and an electrical contact member in said control circuit each rendering the operating mechanism normally inoperative and both the locking detent and the contact member being common to a plurality of series of manipulative operation determining elements, and means for controlling both the detent and the contact member by the operation of a manipulative determining element in any series of the plurality to which said detent and contact member are common independent of the operation of any other determining element in the same series or any other series of such elements.
22. In a machine of the character described, the combination with an electrically driven operating mechanism, an electrical control circuit therefor, and manipulative operation determining elements arranged in a plurality of series and controlling the performance of the operating mechanism, of a mechanically operated locking detent for 55 the operating mechanism and an electrical contact member in said control circuit each rendering the operating mechanism normally inoperative and both the locking detent and the contact member being common to a plurality of series of manipulative operation determining elements, and means for controlling both the detent and the contact member by the operation of a manipulative determining element in any series of the plurality to which said detent and contact member are common independent of the operation of any other determining element in the same series or any other series of such elements, and a second mechanically operated locking detent and a second electrical contact member in said circuit each 60

rendering the operating mechanism inoperative, and means for controlling both the second mentioned detent and the second mentioned electrical contact member by the

5 operation of a manipulative determining element in a separate series of said elements independent of the operation of a determining element in any other series of elements.

23. In a machine of the character described, the combination with electrically actuated operating mechanism and manipulative operation determining elements separated into different series controlling the performance of the operating mechanism, of 10 interlocking means between the respective series of determining elements whereby one series will be normally unlocked and the remaining series normally locked against operation, said interlock means being under 15 the control of the normally unlocked series of operation determining elements, an electrical contact member controlling the operating mechanism, said contact member being also under the control of a determining element of the normally unlocked series whereby 20 the operating mechanism and the succeeding series of operation determining elements will be simultaneously rendered operative by the operation of a determining element of 25 the normally unlocked series.

24. A registering and accounting machine embodying a normally locked operating mechanism and a series of value determining elements and a series of identity determining elements controlling the performance of 30 said mechanism, characterized by two independent locking detents for said mechanism each wholly controlled by one series of said determining elements and simultaneously 35 engaged in locking relation with the operating mechanism necessitating the operation of a determining element in each series before the operating mechanism can be actuated.

40 25. In a machine of the character described, the combination with electrically actuated operating mechanism including a plurality of alternatively selectable registers, an operation determining element controlling the performance of the operating mechanism and a movable register selective element, of a locking detent for the selective element, and an electrical contact member controlling the electrically actuated operating mechanism, both the contact member and 45 the detent being under the control of an operation determining element independent of the manipulation of the register selective element whereby the detent will be engaged 50 with the register selective element and the contact member will be operated by the operation of a determining element of said plurality.

26. In a cash register, the combination 55 with operating mechanism and a series of

value keys and a series of identification keys controlling the performance of the operating mechanism, of an electric motor under the joint control of the value and identification keys, thereby necessitating the operation of a key in each series before said mechanism may be operated.

27. In a machine of the character described, the combination with an operating mechanism including a plurality of alternately selectable registers, an operation determining element controlling the performance of the operating mechanism and a movable register selecting element, a notched detent plate within the notches of which the selective element may be engaged in different positions of adjustment, said plate and selective element being relatively movable in relation one with the other to effect the engagement and disengagement of the selective element in the said notches, and means for controlling the relative movement of the notched plate and selective element by the operation of said operation determining element.

28. In a machine of the character described, the combination with an operating mechanism including a plurality of alternately selectable registers, an operation determining element controlling the performance of the operating mechanism and a movable register selecting element, a movable notched detent plate within the notches of which the selective element may be engaged in different positions of adjustment, and means for shifting said notched plate out of engaging position by the operation of said operation determining element.

29. A registering and accounting machine embodying an operating mechanism the performance of which is controlled by a plurality of setting elements for values and setting elements for identification, characterized by a plurality of independently operated operation prevention devices normally in simultaneous engagement with the operating mechanism and disengaged solely by the operation of a value setting element and an identification setting element respectively, and preventing a registration of said operating mechanism unless one of each of said setting elements has been operated.

30. In a cash register the combination with operating mechanism and a series of value keys and a series of identification keys controlling the performance of the operating mechanism, of an electric motor under the joint control of the value and identification keys, and independent locking detents for said mechanism independently disengaged by the operation of a value and identification key respectively, thereby necessitating the operation of a key in each series before the operation of said mechanism can be effected.

31. In a cash register the combination with operating mechanism and a series of value keys and a series of identification keys controlling the performance of the operating mechanism, of an electric motor under the joint control of the value and identification keys, and mechanical locking means for the operating mechanism also under the joint control of the value and identification keys, thereby necessitating the operation of both a value and an identification key before the mechanism can be actuated.

32. In a cash register, the combination with operating mechanism and a series of value keys and a series of identification keys controlling the performance of the operating mechanism, of an actuating motor for said mechanism, a control member for said motor controlled by one series of keys and an independent control member for the operating mechanism operated by the other series of keys, thereby necessitating the operation of both a value and an identification key before the mechanism can be actuated.

33. In a cash register, the combination with operating mechanism and a series of value keys and a series of identification keys controlling the performance of the operating mechanism, of an actuating motor for said mechanism, a plurality of independently operated control members under the joint control of the value and identification keys normally rendering both the motor and the operating mechanism inoperative, thereby necessitating the operation of both a value and an identification key before the mechanism can be actuated.

34. In a cash register, the combination with operating mechanism and a series of value keys and a series of identification keys controlling the performance of the operating mechanism, of an actuating motor for said mechanism, a lock for the operating mechanism and an independent control

member for the motor independently controlled by the respective series of keys thereby necessitating the operation of a key of each series before the mechanism may be operated.

35. In a cash register, the combination with operating mechanism and a series of value keys and a series of identification keys controlling the performance of the operating mechanism, of an actuating motor for said mechanism, a series of selectable registers, a selective element for said registers, a control member for the motor, and an independent detent for the operating mechanism independently controlled by keys of the different series, and a lock adapted to hold the selected register in operative position after the independent motor control member and the mechanism detent have been independently operated by the manipulation of a key in each series.

36. In a cash register, the combination with operating mechanism and a series of value keys and a series of identification keys controlling the performance of the operating mechanism, of an actuating motor for said mechanism, a series of selectable registers, a selective element for said registers, a control element for the motor under the control of one series of keys, a locking detent for the operating mechanism under control of the other series of keys, thereby necessitating the operation of a key of each series before the mechanism can be actuated, and means to prevent the operation of a key of one series until the register selecting operation has been completed.

In testimony whereof I affix my signature in presence of two witnesses.

HENRY S. HALLWOOD.
